(57) **CLAIM**

I claim the ornamental design for sash rail lock, as shown.

DESCRIPTION

FIG. 1 is a front perspective view of a sash rail lock according to a first embodiment of the invention;

FIG. 2 is a top plan view of the sash rail lock depicted in FIG. 1;

FIG. 3 is a side elevation view of the sash rail lock depicted in FIG. 1;

FIG. 4 is a rear elevation view of the sash rail lock depicted in FIG. 1;

FIG. 5 is an opposing side elevation view of the sash rail lock depicted in FIG. 1;

FIG. 6 is a front elevation view of the sash rail lock depicted in FIG. 1;

FIG. 7 is a front perspective view of a sash rail lock according to a second embodiment of the invention;

FIG. 8 is a top plan view of the sash rail lock depicted in FIG. 7;

FIG. 9 is a side elevation view of the sash rail lock depicted in FIG. 7;

FIG. 10 is a rear elevation view of the sash rail lock depicted in FIG. 7;

FIG. 11 is an opposing side elevation view of the sash rail lock depicted in FIG. 7; and,

FIG. 12 is a front elevation view of the sash rail lock depicted in FIG. 7.

The broken lines shown in the drawing disclosure are for illustrative purposes only and form no part of the claimed design.
